DESIGN FOR A BURNER HEAD

Robert E. Schoenberger, Shaker Heights, Ohio, assignor to The W. J. Schoenberger Company, Cleveland, Ohio, a corporation of Ohio

Application June 12, 1940, Serial No. 92,955

Term of patent 7 years

To all whom it may concern:

Be it known that I, Robert E. Schoenberger, a citizen of the United States, residing at Shaker Heights, in the county of Cuyahoga and State of Ohio, have invented a new, original, and ornamental Design for a Burner Head, of which the following is a specification, reference being had to the accompanying drawing, forming part thereof, and in which drawing:

I claim:

The ornamental design for a burner head, as shown.

ROBERT E. SCHOENBERGER.
